UNITED STATES PATENT OFFICE.

JOHN E. SHARP AND ALVIN J. BASSETT, OF MILWAUKEE, WISCONSIN.

FUEL FEEDER FOR GAS GENERATORS.

Application filed October 2, 1920. Serial No. 414,315.

To all whom it may concern:

Be it known that we, JOHN E. SHARP and ALVIN J. BASSETT, both citizens of the United States, and residents of Milwaukee, 5 in the county of Milwaukee and State of Wisconsin, have invented certain new and useful Improvements in Fuel Feeders for Gas Generators; and we do hereby declare that the following is a full, clear, and exact 10 description thereof.

Our invention relates to gas producing apparatus and particularly to fuel feeding mechanism for a gas producing generator.

It is the object to provide improved mechanism for feeding fuel to a grate and for cleaning the grate of the remains of burnt fuel, and to this end we provide means whereby the fuel feeding mechanism and the grate clearing mechanism may be operated in unison or separately, as desired, or as occasion may demand, and whereby a predetermined amount of fuel is delivered to the grate intermittently at evenly spaced intervals.

25 Our invention is susceptible of embodiment in a variety of mechanical structures, one of which is illustrated in the accompanying drawings, but it is to be understood that the structure shown is merely 30 intended to disclose the essential features of our invention and that its scope is as defined by the appended claims.

In the drawings, wherein like characters of reference denote corresponding parts in 35 the different views:

Figure 1 is a vertical section through a gas producing apparatus equipped with the mechanism of our invention.

Figure 2, a section on the line 2—2 of 40 Figure 1, and

Figure 3, a section showing a modified arrangement of the grate and fuel feed control means.

Referring to the drawings in detail, 10 45 designates generally a generator structure of any well known or preferred design, equipped with rotary grate bars 11, only one of which is shown, and having an opening 12 in its upper wall for the passage of 50 the fuel to be fed to said grate.

The grate bars 11 include terminal shaft extensions 13 and 14 mounted, respectively in bearings 15 provided in opposite walls of the furnace, and the extension 14 of one of 55 these grate bars is provided with a loose sprocket 16 and a clutch member 17 for

locking the sprocket to the extension for rotation therewith, while the extension 13 of each grate bar is provided with a gear 18 meshing with the gear of the next adjacent grate bar whereby all the grate bars are rotated when power is applied to rotate one of them.

Loose on the extension 13 of one of the grate bars is a worm wheel 19 driven by a worm 20 receiving its power from any desired source, and like the sprocket 16 the worm wheel 19 has associated therewith a clutch member 21 for locking the wheel to the extension 13 so as to rotate therewith.

Arranged above the furnace, with its lower open end in line with the opening 22, and rotatably supported within this housing is an open sided hollow fuel feed member 23, a shaft 24 from which extends laterally and is provided with a fixed sprocket 25 connected by a chain 26 with the sprocket 16, whereby rotation of the sprocket 16 will result in rotation of the fuel feed member.

The fuel is fed through the upper end of 80 the housing 22 and when the grate bars are rotated by the worm 20 and worm wheel 19, power will be transmitted to the shaft 24, when the clutch member 17 is in position to lock the sprocket to the extension 85 14, to thereby rotate the fuel feed member 23.

As this latter member is rotated its open side wall alternately aligns with the upper end of the housing and with the opening 90 12 and upon each full rotation will become filled and discharge its contents upon the grate bars. If the clutch member 17 be thrown out of clutching relation with the sprocket 16, the grate bars will rotate, but 95 operation of the fuel feed member will cease, and likewise if the clutch member 21 be thrown out of clutching relation with the worm wheel 19, rotation of the worm will merely turn the worm wheel 19 freely upon 100 the extension 13 with the result that neither the grate bars nor the fuel feed member will be operated. Thus it will be seen that when the fuel feed member is in operation fuel will be fed intermittently at evenly spaced 105 intervals over the grate bars and that since the grate bars themselves rotate, they will be cleaned of the burnt remains of the fuel delivered to them.

In Figure 3, we have illustrated an arrangement in which both the grate control clutch member and the fuel feed clutch

member may be arranged upon the same extension 13 or 14 which carries the worm and worm wheel for transmitting power to the mechanism. In this instance the worm wheel 19' is loose on the extension and has keyed thereon a clutch member 30 adapted to be moved into or out of locking engagement with a sprocket 16' fixed to the extension, and similarly the extension has keyed thereon a clutch member 21' adapted to be moved into or out of clutching engagement with the worm wheel 19'.
10

We claim:

1. In a generator, the combination of a
15 rotatable grate bar, a rotatable fuel feed
member, a sprocket loose on the grate bar,
a connection between said sprocket and said

fuel feed member, a clutch member operable
to lock said sprocket to the grate bar, and
means for rotating the grate bar.

2. In a generator, the combination of a
rotatable grate bar, a rotatable fuel feed
member, a connection between the grate bar
and said fuel feed member, a drive wheel
loose on the grate bar, a clutch operable to
lock the worm wheel to the grate bar, and
means for rotating said drive wheel.

In testimony that we claim the foregoing
we have hereunto set our hands at Mil-
waukee, in the county of Milwaukee and 30
State of Wisconsin.

JOHN E. SHARP.
ALVIN J. BASSETT.
